United States Patent Office.

EDWARD SAVAGE, OF CHICAGO, ILLINOIS.

Letters Patent No. 82,557, dated September 29, 1868.

IMPROVEMENT IN STEAM-COOKING APPARATUS.

The Schedule referred to in these Letters Patent and making part of the same.

TO ALL WHOM IT MAY CONCERN:

Be it known that I, EDWARD SAVAGE, of Chicago, in the county of Cook, and State of Illinois, have invented certain new and useful Improvements in a Steam-Cooking Apparatus; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to a steam-cooking apparatus for culinary purposes, and consists in arranging a series of three chambers or compartments, one above another, in such a manner that steam may be produced in one, superheated in another, and act upon the vegetables or other articles in the third; and also, in connection with these chambers, of a series of pipes for conducting the water and steam, all as hereinafter more fully explained.

In the drawings—

Figure 1 is a top plan view of my steamer, with the cover removed, and several of the vessels for holding the vegetables, shown in position inside.

Figure 2 is an end elevation, and

Figure 3 is a longitudinal section, taken through the centre, the steamer being shown in perspective.

A represents the main or cooking-chamber, rectangular in shape, and having a removable lid or cover, c. Below this chamber is another smaller one, cylindrical in shape, and attached steam-tight to the under side of A, and connected to it by the pipe d only. In this vessel the water is placed, and the steam generated, the water being introduced by removing the cover of chamber A, and pouring the water in through pipe d, said pipe reaching below the surface of the water, and nearly to the bottom of the chamber B, so that no steam can escape through it. Attached to said chamber, B, at the lower side, is a coil of iron pipe, g, one end of which just comes flush on the inside of the bottom, but the other projects up some distance on the inside, as clearly shown in fig. 3, thus keeping up a constant circulation of water through the coil, when heat is applied.

The steam, after being generated in the chamber B, passes down through the elbow-pipe e into another smaller cylindrical chamber, C, which chamber, together with the coil g, sets down in the stove or furnace, and is subjected to the direct action of the fire, and there superheated, then, passing up through the pipe f, acts upon the articles in the chamber A.

The vessels containing the articles to be cooked are supported, in the chamber A, upon a rack, a, so that the steam may surround and act upon them from all sides.

The bottom of the chamber A inclines downward from all sides toward the centre, where the pipe d is placed, and thus any water resulting from condensation of steam will run down through pipe d back into the boiler or generating-chamber B.

To prevent any water from getting into the superheating-chamber from the chamber A, the end of the pipe f is brought some distance up above the bottom of said chamber, as shown in fig. 3.

A steamer thus constructed is found to be a very superior article, as the steam is generated very rapidly by the aid of the coil, and by using superheated steam, the vegetables are cooked much quicker than by the old style, and are left dry and mealy—a very important result.

The articles may be placed in open vessels, or in closed ones, and thus cooked by the heat, without being subjected to moisture, and as they are all placed side by side in a single chamber, they may be examined with no trouble, except lifting the cover e—a great improvement on those styles in which the vessels were placed one above another, and to examine one of which, all those above it must be removed.

Having thus described my invention, what I claim, is—

1. The superheating-chamber C, located at or near the bottom of the cooking-apparatus, substantially as described.
2. The combination of the chamber A, water-vessel B, and steam-chamber C, connected by the pipes d e f, all arranged to operate substantially as and for the purpose set forth.
3. The combination of the coiled pipe g, superheating-chamber C, water-vessel B, and cooking-chamber A, with the pipes e, f, and d, all arranged for joint operation, substantially as described.

EDWARD SAVAGE.
